UNITED STATES PATENT OFFICE

CHARLES A. FREDERICKSON, OF MOUNT VERNON, NEW YORK, ASSIGNOR TO R. HOE & CO., INC., OF NEW YORK, N. Y., A CORPORATION OF NEW YORK

INKING MECHANISM

Application filed November 1, 1927. Serial No. 230,241.

This invention relates to certain improvements in inking mechanism for printing machines.

In certain types of inking mechanism there is provided a distributor, usually in the form of a cylinder or roll, which runs at press speed in contact with the form cylinder of the press. This distributor is inked by a transfer roll which moves between the distributor 10 and a fountain roll located in an ink fountain. This fountain roll is given an advancing feeding movement, this feeding movement being very much slower than the movement of the distributor. The transfer roll 15 contacts with the fountain roll during its period of rest and, as the transfer roll is running at or close to the speed of the distributor roll, this contact is apt to unduly speed up the fountain roll so that the fountain roll 20 will feed too much ink.

It is the special object of the present invention to provide a mechanism for preventing the speeding up of the fountain roll through its contact with the rapidly running transfer 25 roll, this being effected automatically.

A further object of the invention is to provide such a construction embodying few parts, and in which a brake mechanism is employed for braking the fountain roll at the 30 proper time.

With these and other objects not specifically referred to in view, the invention consists in certain novel parts, arrangements and combinations which will be described in connection with the accompanying drawings and the novel features pointed out in the claims 35 hereunto annexed.

In these drawings,—

Figure 1 is an end elevation of so much of 40 an inking mechanism, with the improved roll retarding devices applied thereto, as is necessary for an understanding of the invention;

Figure 2 is a detail plan view, partly in section, of the construction shown in Figure 1, 45 looking in the direction of arrow 2 of that figure;

Figure 3 is a detail end view showing a modification, and

Figure 4 is a side view of the construction 50 shown in Figure 3, in direction of arrow 4.

Referring now to these drawings and first to Figures 1 and 2, which show the invention in its preferred form, the inking mechanism will include a distributor 1 mounted on a shaft 2 suitably supported in framing 3, this distributor acting to deliver ink to the form member of a printing couple, not illustrated. 55

In the inking mechanism illustrated the ink supply is maintained in an ink fountain 4 in which is mounted a fountain roll 5 which is intermittently operated to feed ink through connections hereinafter referred to. Ink is delivered from this fountain roll 5 by a transfer or ductor roll 6 which moves between the fountain roll 5 and the distributor 1. In the particular construction illustrated, this movement of the roll 6 is a vibratory movement, the roll oscillating between the distributor and the fountain roll. This roll is oscillated in any suitable manner, as by being carried in arms 7 on a rock shaft 8, this rock shaft being rocked by a cam roll 9 supported in arms 10 fast on the shaft 8, this cam roll being actuated by a cam 11, which is rotatably mounted on a shaft 12. This shaft 12 is driven by a worm wheel 13 from a worm 14 on the shaft 2 of the distributor 1, before referred to, the shaft 12 being suitably supported in a housing 15 supported from the side frames 3. 70 75 80

The distributor 1 runs at the speed of the form cylinder, that is, press speed, and this speed is relatively high, and the ductor roll in coming in contact with the distributor 1 is brought up to this relatively high speed. 85 The fountain roll 5, however, runs at a very much lower speed and it is desirable that this low speed be maintained during the operation of the mechanism. In accordance with the invention, therefore, means are provided whereby the fountain roll is prevented from running ahead when the rapidly rotating transfer roll 6 comes in contact with the fountain roll 5 to receive its supply of ink. While 90 95 the particular construction for effecting this may be somewhat varied, in the preferred form means will be provided for automatically retarding the fountain roll at the time the transfer roll comes in contact therewith, 100

such time being the period of rest of the fountain roll.

In the particular construction illustrated, the fountain roll is intermittently driven by a ratchet 16, which is keyed by a key 17 to the shaft 18 of the fountain roll. This ratchet is operated by a pawl 19 pivoted at 20 to an arm 21 loose on the shaft 18. This arm 21 is operated by a crank pin 22 carried on the face plate 23 on the shaft 12, before referred to, by means of a link 24 and a ball joint 25 secured to the arm. The forward feeding movement of the fountain roll at each movement of the arm 21 is controlled by means of a pawl cam 26, which can be adjusted by means of a rod 27 having adjusting notches 28, which may be set over a pin 29 carried on a bracket 30. The pawl is provided with a roll 31 which runs onto cam 26, the pawl being held out of engagement with the ratchet until the roll 31 hits the low point 32 of the cam 26. The position of this low point 32 can be adjusted by means of the rod 27.

Various means may be employed for preventing the speeding up of the fountain roll when in contact with the transfer roll, but in the particular construction shown a simple and effective means is a brake which engages with a drum on the end of the fountain roll shaft. As shown, this shaft 18, at its end, is provided with a drum 33 over which is passed a brake strap 34. One end of this brake strap is secured to a bracket 35, and the other end of this strap is provided with an adjusting screw 36 and an adjusting nut 37. Arranged to contact with this adjusting screw is an abutment in the form of a lug 38 which is secured to the arm 21, before referred to, the parts being arranged so that the lug engages the screw and tightens the brake strap when the parts are in the position shown in Figure 1, that is, when the pawl is in retracted or non-feeding position and the fountain roll 5 is at rest. When, however, the arm 21 is rocked forward by the crank mechanism to effect a feeding movement of the fountain roll 5, the lug is moved out of engagement with the screw 36 and the brake released, so that the fountain roll may have the desired freedom of rotation during this feeding movement.

The parts are so timed that the transfer of ductor roll 6 comes in contact with the fountain roll 5 when the latter is in non-feeding position and takes the ink therefrom, the brake straps retarding the undue rotation of the fountain roll during this contact of the parts. As, however, the transfer roll 6 moves to contact with the distributor 1, the pawl is brought into feeding engagement with the ratchet to effect a forward movement of the fountain roll 5, and the brake at this time is released.

In Figures 3 and 4 a slight modification

of the construction above described is shown. In this construction one end of the brake band is fastened or anchored as in the construction of Figures 1 and 2, but the other end is carried directly on the arm 21 instead of being operated by the lug, as above described.

While the invention has been shown and described in its preferred forms, it will be understood that certain variations may be made in the form and arrangement of the parts of the braking or retarding mechanism shown without departing from the invention as defined in the appended claims.

What I claim is:

1. In an inking mechanism, the combination of a distributor, an ink fountain, a fountain roll running at a lower speed than the distributor, a transfer roll taking ink from the fountain roll and delivering it to the distributor, and a friction brake for automatically and intermittently preventing the speeding up of the fountain roll when the transfer roll is in contact therewith.

2. In an inking mechanism, the combination of a distributor, an ink fountain, a fountain roll running at a lower speed than the distributor, a transfer roll oscillating between the fountain roll and the distributor, a friction brake for the fountain roll, and means for actuating the brake to retard the fountain roll when the transfer roll is in contact therewith.

3. In an inking mechanism, the combination of a distributor, an ink fountain, a fountain roll running at a lower speed than the distributor, a transfer roll oscillating between the fountain roll and the distributor, a pawl and ratchet for advancing the fountain roll with an intermittent movement, means for operating the pawl, braking means for the fountain roll, and means actuated from the pawl operating means for tightening and releasing the braking means.

4. In an inking mechanism, the combination of a distributor, an ink fountain, a fountain roll running at a lower speed than the distributor, a transfer roll oscillating between the fountain roll and the distributor, a pawl and ratchet for advancing the fountain roll with an intermittent movement, an arm for operating the pawl, a friction brake for the fountain roll for stopping the fountain roll when the transfer roll is in contact therewith, and connections between the arm and the braking means operating to brake the fountain roll when the transfer roll is in contact therewith and to release the brake when the arm is operated to advance the pawl.

5. In an inking mechanism, the combination of a distributor, an ink fountain, a fountain roll, a transfer roll oscillating between the fountain roll and the distributor, a pawl and ratchet for intermittently advancing the fountain roll, and a brake strap for the fountain roll.

tain roll tightened when the roll is stationary and released when it is advanced.

6. In an inking mechanism, the combination of a distributor, an ink fountain, a fountain roll, an oscillating transfer roll, an operating shaft, a cam for oscillating the transfer roll, a crank operated from the shaft, an arm operated by the crank, a pawl and ratchet advanced by the arm for advancing the fountain roll with an intermittent motion, and a brake strap actuated by the arm to retard and release the fountain roll.

7. In an inking mechanism, the combination of a distributor, an ink fountain, a fountain roll, an oscillating transfer roll, a pawl and ratchet for advancing the fountain roll, an arm for operating the pawl, a brake strap for the fountain roll anchored at one end, an adjustable member on the other end of the strap, and means on the arm engaging the member to tighten the strap.

8. In an inking mechanism, the combination of a distributor, an ink fountain, a fountain roll, a transfer roll oscillating between the fountain roll and the distributor, a pawl and ratchet for intermittently advancing the fountain roll, and a friction brake for the fountain roll acting to retard the fountain roll while the transfer roll is in contact therewith and to release the fountain roll when it is advanced by the pawl and ratchet.

In testimony whereof, I have hereunto set my hand.

CHARLES A. FREDERICKSON.
